(57) **CLAIM**

The ornamental design for a gearbox, as shown.

DESCRIPTION

The claimed gearbox is used for casing a system of gears. FIG. 1 is a front elevational view of a gearbox showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
